APPARATUS FOR ROLLING SHEET METAL

Lawrence C. Steele, Union, W. Va.

Application February 8, 1935, Serial No. 5,538

25 Claims. (Cl. 80—47)

This invention relates to the art of rolling metal and especially to the art of rolling sheets, sheet bars, tin plate and the like. More particularly, the invention relates to a means and method for passing metal in the form of sheet bars, sheet packs, sheets and the like, through, around and about the rolls of a roll stand with such speed, accuracy and certainty that the rate of production, the efficiency of the rolls and the quality of the product will all be greatly enhanced, while at the same time the cost of the rolling operations will be greatly reduced as compared to present practices.

The general object of my invention is the provision of a machine and a method for feeding metal to the rolls of a roll stand rapidly, accurately and positively.

Another object is the provision of a machine and method whereby the metal may be passed between the rolls, caught on the other side of the rolls, and fed again between the rolls with such rapidity that a great number of passes of the metal can be made without reheating being required.

Another object is to provide a method and machine whereby a greater weight of metal can be fed to the rolls for each pass, so that a smaller number of passes per ton of finished product will be required, thereby resulting in a longer tonnage life of the rolls and greater accuracy of the finished product, as well as substantial savings in heat, power and lubricants.

Another object is to provide a machine in which the metal is accurately aligned before being fed to the rolls, thereby insuring accuracy of the finished product and minimizing the amount of scrap.

Another object is the provision of a substantially fool-proof machine having automatic protective devices whereby the machine is self-protected and cannot be injured.

Another object is the provision of a machine adapted automatically to match and align bars, sheets or other material and feed them to the rolls in the form of packs.

Another object is the provision of a machine which is adapted to handle simultaneously pairs of bars, packs or sheets, and to feed such pairs through the rolls in rapid succession whereby the rolls are utilized a large percentage of the time.

Another object is the provision of a feeder and a catcher coordinated therewith in such manner that the catcher will always be ready to receive sheets delivered from the roll stand and the feeder

will always be ready to receive sheets fed by the catcher back to the feeder.

Various other objects and advantages of my invention will become apparent from the following description in which I describe a preferred form of my method and machine, reference being made to the accompanying drawings. It is to be understood, however, that the following detailed description is not to be construed as limiting my patent in any way, but is only given by way of an example both with respect to the machine and to the method. The scope and essential characteristics of my invention are defined in the appended claims.

In the drawings, Figure 1 is a diagrammatic plan view of an illustrative layout of heating furnace, conveyor, rolls, feeder and catcher and the like; Fig. 2 is a side elevation, partly in section, illustrating the relative positions of the feeder, catcher and roll stand; Fig. 3 is a side elevational view of the feeder positioned in front of the rolls; Fig. 4 is a vertical longitudinal sectional view of the feeder taken adjacent to the center dog chain, as indicated by the line IV—IV of Fig. 5; Fig. 5 is a vertical transverse section through the feeder; Fig. 6 is a plan view partly in section, illustrating the conveyors and pushers of the feeder; Figs. 7 and 8 are side and end elevational views, respectively, of the side matching mechanism, the conveyor chains being indicated diagrammatically in Fig. 8; Fig. 9 is a sectional view, on an enlarged scale, of the center dog chain and supporting guideway, taken on the line IX—IX of Fig. 6; Fig. 10 is a similar sectional view of the pushers, taken on the line X—X of Fig. 6; Fig. 11 is a detail side elevation illustrating a sheet-retarding mechanism; Fig. 12 is a side elevational view of the feeder driving mechanism; Fig. 13 is a vertical sectional view of the driving mechanism taken along the line XIII—XIII of Fig. 12; Fig. 14 is a horizontal sectional view taken along the line XIV—XIV of Fig. 12; Fig. 15 is a transverse section on the line XV—XV of Fig. 6, showing the drive shaft for conveyor chains and center dog chains; Fig. 16 is an enlarged side elevational view of the catcher, in position in back of the roll stand; Fig. 16A is a plan view of the catcher, partially in section; Figs. 17 and 18 are detailed side and end elevations, respectively, of an auxiliary feeding mechanism provided to insure the proper delivery of the sheets, packs or bars into the rolls, and Fig. 19 is a more or less diagrammatic elevation illustrating the manual control system.

Referring to the drawings, in Fig. 1, I have

diagrammatically illustrated a layout of the several elements of a rolling mill in which I prefer to practice and carry out my invention. Such a layout or arrangement is well adapted to rolling 5 tin plate for example. If tin plate were to be rolled from the usual 8" sheet bars, a number of such bars would be fed through the bar furnace at the left of the figure and when properly heated, would be conveyed preferably in pairs to the 10 feeder in front of the roll stand.

According to my method, the bars, sheets, or other material so delivered to the feeder are squared up and spaced from each other and successively passed through the rolls to the catcher and returned to the feeder for succeeding passes; one unit of material being passed through 15 the rolls while the other unit is being returned to the front of the rolls for a succeeding pass.

The feeder and catcher handle the material so 20 rapidly and effectively that the bars are quickly transformed into sheets, are matched in the feeder and passed thereafter as a pack through the rolls as many times as desired and thereafter delivered by the catcher to the platform marked 25 "Hinged platform", "Opening platform" at the rear of the catcher. I prefer that the platform onto which sheets are delivered from the catcher be elevated so as to be substantially on a level with the upper part of the catcher (see Fig. 2) 30 from which the rolled sheets are delivered. The sheets being so delivered onto the platform may be doubled in the "Doubler" and if necessary trimmed in the "Shear", preferably located with relation to the platform as shown.

35 At this point in the manufacture of tin plate, for example, the two original sheet bars will have been transformed into a four-ply doubled pack which may then be conveyed from the platform on the conveyor to the rear of the furnace where 40 the doubled pack is sent through the pack furnace for reheating to rolling temperature. While I have indicated diagrammatically two furnaces, I contemplate that a single furnace, which may be provided with parallel conveyors, one for handling 45 packs and another for handling sheet bars, may advantageously be employed. Of course, the particular type of furnace forms no part of this invention.

As noted above, my feeder and catcher can 50 handle a pair of sheet bars simultaneously to effect the rapid succession of passes of such bars. The same is true of the ability of the feeder and catcher to handle packs and sheets. Thus to 55 continue with the illustrative description of the manufacture of tin plate, a pair of doubled four-ply packs can be conveyed from the pack furnace to the feeder, and as will hereinafter more fully appear the feeder will pass one pack through the rolls to the catcher, which will return that pack to the feeder while the feeder is feeding the second pack through the rolls. In this manner, the two 60 packs are quickly elongated by rapidly succeeding passes and may then be matched in the feeder for as many more passes as are found desirable. 65 Thereupon, the catcher will deliver the pair of matched, doubled packs to the platform where, if further reduction in gauge is desired, the matched pack then comprising the substance of four sheet bars and being an eight-ply pack may be doubled into a sixteen-ply pack, sheared and trimmed and returned to the furnace for another 70 heat.

Such a pack along with a similar pack can again 75 be passed through the rolls by the feeder and

catcher, and if desired matched in the feeder and rolled again as a thirty-two-ply pack. In each case, I prefer to handle the bars, sheets or packs in pairs substantially throughout the rolling operation in order to minimize the idle time of the rolls and speed up the rolling operations. The 10 packs having thus been reduced to tin plate gauge may be removed, sheared, and opened or separated in the usual manner.

While the foregoing has dealt largely with the manufacture of tin plate by way of example, it 15 will be seen that the above layout is adaptable to the manufacture of sheets of various sizes and descriptions. However, in the following description, I shall refer particularly to the manufacture 20 of tin plate, because such manufacture presents extraordinary problems and is suitable to illustrate the distinct advantages of my invention.

In Fig. 2 of the drawings, I have somewhat diagrammatically illustrated a preferred embodiment 25 of my apparatus insofar as the coaction between the feeder, the rolls, and the catcher, and the general construction of the feeder and the catcher are concerned. The feeder 1 is positioned at the left or in front of a two high mill (shown 30 by way of example) comprising rolls 2 and 3 supported in the usual manner on the roll stand 4. At the rear of the mill (to the right in the drawing) I illustrate the catcher 5 which may follow in a general way the teachings of my prior Patent 35 No. 1,487,819.

The feeder and the catcher will both be described in detail in later pages of this specification. For the present it will suffice to say that the feeder 1 is preferably constructed as a movable unit which may be advanced on suitable rails 6 toward or away from the roll stand, both for the sake of adjustment and for repair or replacement of the rolls and the like. Sheets, 40 packs, bars, or bars for breakdowns, or any other suitable material (which will hereinafter be collectively referred to as "material") from the furnace are delivered to the conveyor chains 7 and by means of mechanisms to be hereinafter described, are properly spaced, centered, squared 45 up, and fed into the bite of the rolls.

The rolled metal leaving the rolls as indicated by the arrow rocks the flag 8 of the catcher and holds the flag depressed until the trailing edge of the material being then moved by the conveyor chains 9 onto the skid bars 9a of the catcher, permits the flag 8 to be raised by the spring 8a. The depressing and subsequent raising of the flag 8 to the position shown in Fig. 2, establishes an electrical circuit which causes the carrier 10 of the catcher to rotate a half revolution in a clockwise direction as viewed in Fig. 2, lifting the rolled material into contact with the conveyor chains 11 which, by their coaction with the carrier conveyor chains 12 deliver the material to the additional conveyor chains 11a and 13 which lie over the top of the roll 3 and convey the material to the left or from back to front as indicated by the arrow over the top roll thus delivering the material to the feeder 65 carrier arms 14.

The material in its movement from the catcher to the feeder contacts with the dog or flag 15, raising it up as the material passes therebeneath and permitting it to drop as the trailing edge of the material is ejected from the conveying chains of the catcher. This movement of the flag or dog 15 mechanically controls retarding devices indicated generally at 17 (Figs. 3 and 11) which are provided to prevent the 70 75

material from traveling too far on the arms 14, and the movement of the flag also establishes an electrical circuit which causes the carrier 18 of the feeder to rotate a half revolution in a clockwise direction swinging the carrier arms 14 downwardly as viewed in Fig. 2, and depositing the material on the endless conveyor chains 7 which advance the material back into the rolls for another pass.

10 Thus the act of the catcher 5 in delivering the material to the feeder 1 causes the actuation of the feeder to redeliver the sheet through the rolls back to the catcher. It will further be seen that the reception by the catcher of the material 15 from the feeder via the mill rolls initiates the operation of the catcher to deliver the material back to the feeder; the three major elements of this combination, to-wit, feeder, catcher and rolls 20 all being interdependent upon each other for the continued rolling and re-rolling of the sheets. Furthermore, as the feeder is provided with two sets of arms 14, one piece of material may be delivered to the conveyor and thence to the rolls, while another is being received from the 25 catcher, thus making it possible to carry out my method by handling material, whether breakdowns, bars, sheets or packs, in pairs throughout substantially the entire rolling operation.

In addition to the automatic controls mentioned above, various manual controls are provided and the mechanisms are provided with slip clutches, interlocking controls and other safety devices to prevent damage to the machine or to the material. Also, the catcher is provided 35 with means, controllable either automatically or manually, for delivering material to the platform to the right of the catcher.

Conveying mechanism

40 Referring now to the feeder per se and to Figs. 3 and 4 of the drawings, it will be seen that the body of the feeder preferably comprises a base 20 provided with suitable upright supporting elements 21 all carried by car wheels 22 operating 45 on the tracks 6. A motor 23, along with suitable reduction gearing and driving mechanisms, all indicated generally at 24 and illustrated in greater detail in Figs. 12 to 14, inclusive, may be mounted on suitable castings 25 carried on the 50 base of the feeder.

The various mechanisms for horizontally conveying, centering and aligning the sheets, and for feeding them into the bite of the rolls are all driven by the longitudinally extending shaft 55 26, which in turn is driven by the motor 23 through suitable worm reduction gearing 27, a shaft 28, bevel gearing 29, the downwardly-extending shaft 30 (see Figs. 12, 13 and 14), and bevel gearing 31 (see Figs. 3 and 6).

60 The shaft 32, which drives the main conveyor chains, is journalled in suitable bearings in the frame base 20, as at 33, and has mounted on it a pair of sprockets 34, a centrally located sprocket 35 and a bevel gear 36 at one end, as indicated 65 in Fig. 15, which meshes with a bevel gear 37, on the end of the shaft 26. A friction clutch 38 is provided in the shaft 26 to allow the shaft 32 to remain stationary, while the shaft 26, continues to rotate, if the material is caught or if 70 a blockade occurs in the feeder. The tension in the friction slip clutch, which may be of any ordinary construction, is set so as to avoid injury either to sheets being fed or to any of the elements of the feeder which are actuated or 75 driven by the shaft 32. Passing around the

sprockets 34 and driven thereby are the main endless conveyor chains 7 which also pass over a pair of sprockets 39 carried by studs 40 (Fig. 6) which are elevated above and longitudinally offset from the shaft 32.

The chains 7 in passing over the sprockets 39 are elevated thereby, and from that point are inclined downwardly toward the mill rolls at an angle preferably less than that at which gravity will cause the material conveyed thereon to slip with relation thereto. Adjacent the mill rolls the conveyor chains 7 pass over a pair of sprockets 41 carried by the shaft 42 which in turn is suitably journaled and supported by the extension frame 43 of the feeder. As shown in Fig. 4, means are provided for taking up the slack in the conveyor chains 7 by suitable adjusting mechanism 44.

The main conveyor chains 7 convey new material from the forward end of the feeder through the feeder to a point adjacent the mill rolls, where sheets of sufficient length will be fed directly into the rolls by these conveyor chains. Pieces of insufficient length will be aided in their movement toward the mill rolls by other means to be presently described. Since the conveyor chains 7 can only force the material into the rolls up to the limit of the static friction between the chains and the sheets or plates, other means to be presently described are provided for making certain that the material is fed between the rolls. In normal operation of the feeder, I prefer that the conveyor chains 7 be driven somewhat faster than the surface speed of the mill rolls. Means are provided, however, for independently varying the speeds of the feeder, rolls, and catcher in order to operate properly under different conditions.

Turning now to the means hereinbefore referred to for aiding the movement of the material to the rolls and for supplementing the action of the main conveyor chains, I provide two independently operable means; the first comprising a pair of pushers 50 lying on opposite sides of the median plane of the feeder and between the conveyor chains 7 (see Fig. 6) and each pusher having a pair of longitudinally-spaced movable dogs 51 (see Figs. 4 and 10), each pivotally supported as at 52 (see Fig. 10) and so balanced that a square surface 53 is presented to such sheets or materials as lie to the right of the pusher dogs as shown in Fig. 4, but which are depressible by the weight of a sheet should the sheet overrun the pusher dogs or be placed on top of them.

Each pusher is moved longitudinally of the feeder in a reciprocating motion through links 54 which are pivotally connected to rock arms 55 carried by rock shaft 56 extending transversely of the feeder and journalled in the base structure of the frame. The shaft is rocked by means of an arm 57 and a link 58, which link is joined at one end to a crank arm 59, rotated through a bevel gear drive 60, from the longitudinally extending shaft 26. The rotary motion of the crank arm 59 is transferred into reciprocating motion of the pushers through the linkage described, the crank arm being driven through a one-revolution clutch 61 of any suitable well-known construction, which is preferably actuated in timed relationship with the movement of the feeder mechanism by means of the cam 62 and cam follower 63 (Fig. 4), link 64, bell crank 65 and links 66 and 67. The clutch may also be engaged manually by mechanism to be hereinafter described.

The pushers, being laterally spaced from each

other, have the faculty of squaring up material to be forced into the rolls just as the material enters the rolls. It will be appreciated that the trailing edge of sheets or bars of different lengths 5 may be engaged by the pushers while the material is in the rolls, and in that circumstance the friction slip clutch 38 will prevent the pushers from injuring the material.

These pushers are particularly intended for 10 moving relatively short sheets or sheet bars into the roll pass inasmuch as sheet bars, for example, may be of such little longitudinal dimension that they might otherwise come to rest after having 15 gone beyond the end of the main conveyor chains 1.

Since the pusher dogs are depressible by sheets or bars which tend to overrun them when being carried by the main conveyor chains or other advancing mechanism at a higher speed than 20 the pushers, their slower movement makes them available to urge material into the rolls, and also provides that the pushers never interfere with any other function of the feeder.

Referring particularly to Fig. 10, each of the 25 pushers 50 slides upon a slotted guide 68 along the surface 69, and each pusher has a depending part 70 lying in the slot of the guide with an enlarged head 71 which keeps the pushers from locking with relation to the guide. Each guide 30 is attached to a part of the main base 20 of the frame structure by suitable means, such as a cap screw 72 as shown. Referring to Fig. 4, the pushing faces 53 are seen spaced from each other in their extreme position of travel towards 35 the mill rolls. It is to be noted that the length of the stroke of the pusher is preferably greater than the longitudinal distance between the pushing faces 53 of the respective pushers so that it would be impossible for a sheet bar, for example, to overlie the leading pushers, and not be pushed by one pusher or the other in the course 40 of succeeding strokes.

The linkage for reciprocating the pushers is such that a modified simple harmonic motion 45 will result so that the pushers obtain a maximum speed in about mid-stroke and zero speed, of course, at the ends of the strokes. To make my feeder particularly adaptable for feeding sheet bars in rolling tin plate, I preferably so arrange 50 the stroke of the pusher with relation to the pass between the rolls that the sheet bar would be advanced rapidly towards the rolls during the middle of the pusher stroke, but would be slowed down to substantially roll surface speed as the 55 bar entered the bite of the rolls.

By such an arrangement, it will also be seen that the sheet bar would encounter the resistance of the rolls only at about the end of the pusher stroke so that slippage of the friction clutch 38 60 in the pusher driving connection will be kept at a minimum.

The third means for advancing material into the rolls comprises a centrally positioned dog chain 73 (see Figs. 4 and 6) driven by the sprocket 65 75 on the main conveyor drive shaft 32 and driven through the friction slip clutch 45 (see Fig. 15). This sprocket, I prefer to make slightly smaller than the sprockets 74 which drive the main conveyor chains 1, so that the dog chain 70 73 will move a little less rapidly than the main conveyor chains. The centrally disposed dog chain 73, as may be seen in Fig. 4, passes over sprockets 74 and 75, and positioned so that the path of the dog chain in between the sprockets 75 74 and 75 is substantially parallel to the path of

the main conveyor chain 1, albeit the dog chain itself is somewhat lower than the exposed surface of the main chains 1. After passing the sprocket 75, the chain is directed downwardly around a forwardly-disposed sprocket 76, thence back to the driving sprocket 35. The forward sprocket 76 is carried on a small sub-frame 77 illustrated in Fig. 4, which is secured to the main frame 20 of the feeder. The sprocket 76 is slidably arranged on the sub-frame and movable forwardly by the adjusting screw 78 to adjust the tension in the chain.

At spaced intervals along the dog chain 73 are pivotally connected dogs 79 (see also Fig. 9), each of which may be substantially channel shaped and overlie the links of the chain, depending on opposite sides thereof.

Each of the dogs is pivotally supported as at 80, and balanced so that the leading edge of each dog tends to rise above the level of the chain. The chain is supported between the sprockets 74 and 75 on an inverted T-shaped track 81 having a flanged base 82, the flanges of which are engaged by the trailing edges of the dogs. After the dogs progress beyond the idling sprocket 74, the shape of the track is altered so that the dogs may attain a more upright position, presenting a face disposed at substantially right angles to the chain. The faces 83 of the several dogs taking the position shown between the sprockets 74 and 75 are adapted to engage the trailing edges of the sheets, bars and the like, and aid them in their progress toward the mill rolls. Since the dog chain travels at a slower speed than the conveyor chains 1, it is not to be expected that the dogs would engage the material unless it is delayed in its progress toward the rolls as, for example, by operation of the side matching mechanism or by other means yet to be described. By reason of the downward deflection of the dog chain after it passes the sprocket 75, the dogs are gradually removed from the path of the material so that there is no danger of the dogs catching on and bending the rear edges of the sheets or bars. The dog chain may be stopped without damaging the material by reason of the slip clutch 45.

In order to insure that the front edges of the sheets, packs, bars, or other material are properly fed into the bite of the rolls, I have provided a mechanism particularly shown in Figs. 4, 17 and 18, which is adapted to engage material having forward edges which have curled upwardly away from the conveyor chains.

This mechanism comprises a pair of spaced chains 85 which travel in the direction indicated by the arrow in Fig. 18 and thus are adapted to properly guide the material downwardly into engagement with the conveyor chains and the toe plate 86, and thence into the bite of the rolls. The chains are preferably supported on sprockets 87 and 88 carried by transversely-extending shafts 89 and 90 suitably journaled in the feeder frame. The shaft 89 is driven from the shaft 42 which supports the forward main conveyor chain sprockets 41 through gears 91 and 92 and chain 93, shaft 94 and chain 95 having the necessary sprockets associated therewith.

The conveying mechanism is also provided with guides comprising bars 96 which are adapted to engage the end of any material overhanging the outer ends of the rotary supports 14 so as to urge any such material onto the arms 14 as they are moved downwardly to insure proper posi-

tioning of the material on the conveyor, the forward end of the material always being deposited on the main conveyor chains behind or to the left as shown in the drawings, of the 5 guiding chains 85 and the bars 96.

Side matching plates

In order to align or match a plurality of sheets with respect to each other as well as to align or center a single sheet or several sheets with 10 respect to the mill rolls, I have provided side matching or aligning mechanism, a preferred form of which is illustrated particularly in Figs. 3, 7 and 8. This mechanism may comprise a pair of oppositely-disposed side plates 97 secured 15 to depending arms 98 which are pivotally suspended as at 99 from brackets 100 which may be suitably supported from the feeder super-structure.

When sheets or other material indicated diagrammatically at S are deposited on the conveyor chains 7, (the chains being indicated diagrammatically in Fig. 8) the matching plates 97 are moved inwardly from opposite sides of the 20 feeder and caused to engage sharply the lateral edges of the sheet or sheets to align or match them.

In order to actuate the side matching plates, the depending arms 98 are each provided with bell crank arms 101 to which are connected 25 cables 102 and 103. The cable 102 is connected directly to the pulley or sheave 104, while the cable 103 is also connected thereto but is passed over intermediate sheaves 105 and 106. Rotation of the pulley 104 will cause the cables to pull 30 down on the arms 101 and thus swing the matching plates into engagement with the sheets on the conveyor, as shown in dotted lines in Fig. 8. In order to adjust the action of the matching plates, turnbuckles 107 are provided 35 for changing the lengths of the cables 102 and 103. The pulley 104 is rotated for a fraction of a revolution by the shaft 26 through suitable reduction gearing 19, (Figs. 3 and 6), shaft 26', and an intermittently engageable friction clutch 108.

The clutch is automatically engaged in timed 40 relationship with the carrier mechanism by means of a cam 109 which raises and lowers a lever 110, which in turn is connected to the clutch actuating mechanism by means of the 45 rod 111 and the bell crank lever 112 (see Fig. 3). A cable 113 is also secured to the bell crank 112 and is extended to the right for connection to a manual control, to be described, and the rod 114 50 is provided with a lost motion connection 114 in order to allow the manual control device to be actuated at any time.

The cam surface is designed so that during 55 every complete revolution of the cam or every half revolution of the carrier mechanism, the clutch will be engaged to rotate the pulley 104 momentarily in the direction indicated by the arrow on Fig. 8 and quickly pull the matching plates toward each other; and, as will be seen from the size and shape of the cam, the clutch 60 is thereafter released and the plates are permitted to move apart to release the sheets whose edges have been engaged and thus to permit continued movement of the sheets toward the mill rolls. The arms 98 and the plates 97 are 65 balanced so that the plates normally hang away from the edges of the sheets.

Spacing and aligning mechanism

As previously pointed out, the feeder is adapted to handle material in pairs, and in order 70

to insure that the separate pieces of material will be properly spaced from each other as well as to properly align and match the material in a longitudinal direction, I have provided an automatically and manually controlled spacing and aligning mechanism, illustrated particularly in Figs. 4 and 19.

This mechanism preferably comprises two pairs of hooks 115 and 116 disposed at the rear and front ends respectively of the main conveyor 10 chains 7. These hooks are supported on rock shafts 117 and 118, respectively, and rocking movement of the shafts moves the hooks out of and into the path of the material carried by the conveying chains, as indicated by the dotted line 15 positions of the hooks as shown in the drawings. The rock shafts 117 and 118 are both operated through a longitudinally-extending rod 119 and suitable bell crank levers 120 and 121.

A spring 122 in engagement with the rod and the frame of the machine constantly urges the hooks to their upper position where they are disposed in the path of movement of material on the conveyor chains. The rod is also provided with a dog 123 which is engageable by a latch 124 so that the hooks may be retained in their lower position, if desired. The movement of the hooks is controlled in timed relationship with the rotation of the rotary carrier mechanism by means of the cam 62 which also controls the operation of the 20 pushers. This cam controls the downward movement of the hooks by engagement with the cam follower 63 which is connected to the downwardly-extending tension member 64 which functions 25 through bell crank lever 125 and lost-motion connection 126 to move the rod 119 to the left as shown in the drawings, thus depressing the hooks. As previously described, this linkage, except for 30 rod 119, controls the engagement of the pusher clutch 61 (Fig. 6), so that the pushers are actuated immediately after the hooks are depressed. A spring 127 (Fig. 19) is employed to maintain the 35 cam follower always in engagement with the cam.

The hooks are released from their depressed 40 position by the action of the cam 62 on the cam follower 128 which, through a suitable system of levers and rods, as shown in the drawings, is adapted to push downwardly on the end of the latch 124 beyond the pivot 129, thus causing the 45 latch to be released from its engagement with the dog 123 and allowing the hooks to be raised into the path of the material by the action of the spring 122.

The hooks 115 and 116 and the latch 124 may 50 be manually controlled either from the end of the feeder through the pedals 130 and 131, respectively (see Figs. 6 and 19) and suitable linkage 130' and 131', respectively, or by the pedals 132 and 133, respectively, which are mounted in the 55 floor of the control pulpit P adjacent to the roll stand, through suitable bell crank levers and cables 132' and 133', respectively. The pedals 130 and 132 also operate the pusher clutch 61 through the interconnections above described, and through the levers 65, 66 and 67, while the 60 side matching plates may be actuated by pedal 134, through bell crank 134' and cable 113, as 65 shown in Fig. 19.

In operation, the hooks are employed to space 70 properly the pairs of sheets, bars, or packs in their travel through the rolls, and, as the hooks are laterally spaced, they function to assist in obtaining proper alignment of the material with re- 75

spect to the axis of the rolls. Furthermore, the hooks and particularly the hooks 116 may be employed in matching plates, bars or packs on the conveyor, for the hooks may engage the forward edges of all the layers of material in a pack while the rear edges are being engaged by the dogs of the dog chain, thus accurately aligning the various plies of material in the pack with respect to each other.

10

Rotary carrier mechanism

As stated above, I preferably provide the rotary carrier mechanism, indicated generally at 18, for receiving the material delivered from the catcher 15 over the top of the rolls and for transferring such material to the conveying and feeding mechanism just described.

As shown particularly in Figs. 3, 4 and 5, the material delivered from the catcher to the feeder 20 is deposited on the carrier arms 14 and by downward rotary swinging motion of the arms is carried to the conveyor chains. The carrier arms 14 are supported on a pair of webs 135 which in turn are mounted upon the cross shaft 136 and 25 are rigidly connected together by transversely extending struts 137 which are positioned adjacent the ends of the webs at diametrically opposite points. One of the struts supports the pair of arms 14 and the other strut supports a similar 30 pair of arms 14' similarly disposed and related to the carrier. As shown most clearly in Fig. 3, the arms 14 and 14' extend substantially tangential to the arc described by the webs 135. It will be noted that considerable space is left between the 35 shaft 136 and the upper surface of the arms 14, as shown in Fig. 4, so that long sheets being delivered from the catcher to the arms 14 may lie thereon and extend through the space between the arms and the shaft and beyond the ends of 40 the arms or to the left, as illustrated in the drawings. In order to support such long sheets, I have provided a guide member comprising a series of plates 138 which slope downwardly at an angle toward the conveyor and rolls, and which are 45 spaced to allow the passage of the arms 14 between them. These plates form an adequate support for the ends of long sheets, and by reason of this construction the machine is adapted to handle sheets or other materials which are materially 50 longer than the over-all length of the arms 14.

The main carrier shaft 136 is journaled at its ends (see Figs. 4 and 5) in upstanding portions of the frame structure, and is driven by the main driving motor through the gear trains and 55 clutches illustrated in Figs. 12 to 14, inclusive, to which detailed reference will hereinafter be made.

When a sheet is deposited on one of the pair of arms 14 and 14' and when its trailing edge has 60 left the catcher and allowed the flag or dog 15 to drop (see Figs. 2 and 3), an electrical circuit is established which rotates the carrier 18 in a clockwise direction, and provision is made, as will hereinafter appear, that the carrier rotate 65 exactly 180° so that the arms 14' assume the position from which the arms 14 have just departed. The arms in their downward rotary motion follow the arc 139 in the direction of the arrow shown in Fig. 4, and pass within the lateral 70 confines of the main conveyor chains 7 (see Fig. 5), and through appropriate slots in the main base 20, and in their passing laterally encompass the pushers 58 and the dog chain.

As I propose to effect a rotation of 180° of the 75 carrier 18 in a very short time, the acceleration

and deceleration of the carrier must necessarily be great. In order to reduce the shocks and jars and resulting wear and tear on the mechanism to a minimum and further to deposit the sheets from the arms 14 onto the conveyor chains in such a manner as to avoid bouncing of the sheets, I have provided the hydraulic check mechanism illustrated particularly in Figs. 4 and 6. This mechanism may comprise a double-acting hydraulic cylinder 140 and having a piston 141 which is connected to a pair of cams or dogs 142 and 143 through a rack and pinion mechanism indicated at 144 and arranged so that movement of the dog 142 in one direction causes the piston to move in the same direction and the dog 143 to move in the opposite direction. Movement of the piston is resisted by the flow of fluid from one end of the cylinder 140 to the other, through the conduit 145. The amount of resistance may be varied by adjusting valve 146.

The cams or dogs 142 and 143 are laterally spaced apart and are engaged by correspondingly spaced cams 147 and 148 carried on the periphery of one of the webs 135. As shown in Fig. 4, the cam 147 has just engaged and passed the cam 142 to check the motion of the rotary carrier as the arm 14 approached position for receiving material from the catcher. This action has moved the cam 142 to the left, as shown in the drawings and caused the cam 143 to move to the right into the position shown, where it is ready to be engaged by the cam 148 to slow down the movement of the carrier as the arm 14 swings downwardly and approaches position for delivering the material to the conveyor chains. Thus, the hydraulic check and shock absorber mechanism assists in stopping the carrier in position to receive material from the catcher and momentarily retards the carrier as the material is being delivered onto the conveyor chains. Similar dogs 40 are provided on the opposite side of one of the webs 135 to similarly retard the carrier as the arms 14' approach corresponding positions.

Sheet retarding mechanism

As the sheets, packs, bars or other material are delivered with considerable velocity from the conveyor chains 11 and 13 of the catcher onto the rotatable arms 14, I have found it preferable to provide a mechanism for preventing the material from sliding too far onto the arms or to the left as shown in the drawings.

This mechanism which is illustrated particularly in Figs. 3, 4 and 11 is especially useful in conjunction with sheet bars such as the sheet bar 8 illustrated in Fig. 3, as it functions to stop the motion of the bars adjacent to the outer ends of the arms 14, and thus the bars are delivered to the conveyor chains as close as possible to the rolls thereby eliminating excessive travel and speeding up the operation of the machine.

As illustrated in the drawings, the mechanism comprises a series of pairs of depending levers 17 pivoted at their upper ends as at 150, and balanced so as to hang in the path of the material delivered from the conveyor to the arms 14. In the position shown in Figs. 3 and 4, the bars are locked in substantially vertical position, by means of a series of segmental members 151 pivoted as at 152 to the frame members 153, so as to positively stop any material which is delivered onto the arms 14. The members 151 are provided with notches 154 which are adapted to engage the upper ends of the depending levers 17, thus restraining the levers against swinging movement.

to the left as shown in the drawings. The locking action of the segmental members is controlled by means of the flag 15 through the rod 155, the pivoted lever 156, link 157, bell crank 158 and link 159 so that when the dog or flag 15 is raised by the passage of material from the catcher to the feeder the link 159 will be moved to the right, thus rotating the segmental members in a clockwise direction and releasing the upper ends of the levers 17 from the engagement with the notches 154.

By reason of this arrangement, as long as the material is passing under the dog 15 thus holding it in raised position, the depending levers 17 are free to swing out of the path of the material and merely exert a frictional retarding action thereon. However, as soon as the rear end of the material has passed the dog 15 it will drop, thus allowing the segmental members to swing downwardly into locking position and positively locking those levers 17 which have not already been raised by the passage of the material. A lost-motion connection is provided between the link 159 and the segmental members by means of the pins 160 secured to the link and the slots 161 in the segmental members so that link 159 may be moved to the left, and any lever 17 which has not been deflected by the passage of material therebeneath may be locked even if members to the right of it have been raised by the passage of the material as shown in Fig. 11.

By this arrangement, the retarding mechanism may merely have a frictional effect on long sheets which slide onto the arms 14 and perhaps onto the supporting bars 138 while shorter bars, packs or sheets will be stopped as soon as their rear edges have passed beyond the flag 15. However, the trailing edges of the material will always lie on the arms 14, for the flag 15 overlies the ends of the arms 14, as shown in Fig. 3.

Thus, all of the material will be deposited on the arms 14 with its outer end closely adjacent the ends of the arms 14 and the material, regardless of its length, will be deposited on the conveyor or chains at substantially uniform distances from the rolls. This eliminates lost motion in feeding the material to the rolls and makes possible rapid and uniform action of the feeder regardless of the length of the material being fed to the rolls.

In order to prevent material from being delivered from the catcher when the arms 14 are not in position to receive it, I have provided the hook member 162 which is pivoted on the frame of the catcher as at 163 (see Fig. 2). The hook is balanced so that the end portion 164 will be positioned in the path of material being delivered by the chains 11 and 13, except when it is depressed by engagement with the cam surfaces 165 on the ends of the arms 14 and 14' (see Fig. 3). Thus there is no possibility of material being discharged from the catcher except when the feeder is ready to receive it.

Driving mechanism

As previously pointed out and as shown particularly in Figs. 12 to 14, inclusive, motor 23 drives the shaft 28 by means of suitable worm reduction gearing. The rotary carrier mechanism 18 is also driven by the motor 23 through the worm reduction gearing, shaft 28 and pinion 167 which meshes with gear 168 mounted on sleeve 169 through a friction slip clutch 170, of any ordinary type. The sleeve 169 in turn drives a concentric shaft 171 through a jaw clutch 172, and the main shaft 136 of the rotary carrier mechanism is driv-

en by pinion 173 keyed to shaft 171 and meshing with gear 174 keyed to the shaft 136.

The starting and stopping of the rotary carrier mechanism is controlled by the jaw clutch 172 which is engaged by the action of the solenoid 175. When the solenoid 175 is energized, the link 176 is raised, thus swinging the lever 177 about its pivot and pulling the pins 178 and 179 downwardly out of engagement with the notch 180 and the cam groove 181, respectively, in the periphery of the clutch member 172.

The disengagement of the pins 178 and 179 allows the clutch member 172 to be moved to the right, as shown in Fig. 13, by the spring 183, thus permitting engagement of the respective driving jaws J of the clutch. As soon as the shaft 171 starts to rotate, the solenoid 175 is de-energized by reason of the actuation of the switch 191 from the cam 169 through the bell crank lever 110 and the link 192 (see Fig. 3). This action allows the pins to move upwardly so that the end of the pin 178 rests on the periphery 184 of the clutch member 172, being held thereagainst by the spring 185. In this position, the roller 186 on the end of the pin 179 lies partly within the groove 181, and when the shaft 171 makes a complete revolution the cam surface 187 engages the roller 186 and thus causes the clutch member 172 to be moved to the left, as shown in the drawings, against the action of the spring 183, thus disengaging the clutch. At the time the clutch is disengaged the pin 178 is forced upwardly into the notch 180, thus stopping the shaft in a definite position. In order to reduce the shocks incident to stopping the shaft and the rotary carrier mechanism and in addition to the hydraulic check mechanism, previously described, the pins 178 and 179 are pivotally mounted on a shaft 188 and are held against rotation by means of a link 189 which is connected to the spring shock absorbing mechanism 190.

In the embodiment shown, the shaft 171 makes two revolutions for each revolution of the rotary carrier 18, and thus each time the solenoid 175 is energized the mechanism just described will permit one complete revolution of the shaft 171 and therefore a one-half revolution of the rotary carrier mechanism.

The solenoid 175 may be energized to start the operation of the ferris wheel by means of manually controlled switches, not shown, disposed at the rear end of the machine and also on the pulpit. The automatic operation of the solenoid is controlled by the flag 15 (Fig. 3), through the link 155 and lever 156 which actuates the switch 93. The flag, as previously described, is actuated by the movement of material from the catcher to the feeder, and the switch 193 is arranged so that the solenoid is energized by the raising and subsequent falling of the flag 15 after the material has passed therebeneath. However, it is to be noted that the automatic action of the flag switch can be cut out by the manual controls heretofore mentioned.

Catcher mechanism

Referring to Figs. 16 and 16A, it will be seen that the catcher comprises a suitable wheeled base adapted to run on track rails, so that the catcher may be readily moved into and out of operative position relative to the rolls 2 and 3. Upright supporting housings or casings 200 and 201, enclosing driving mechanism, are mounted on the base at the sides thereof, and a horizontal cross shaft 202 is suitably journaled in the cas-

ings. A motor 203 is carried by the housing 200 and has a worm driving connection with a worm wheel 204 that is secured to the shaft 202, to effect continuous rotation of the shaft. 5 The carrier 10 is rotatably mounted on the shaft 202 and includes a sleeve or spool 205 through which the shaft 202 extends and is provided with end plates or flanges 206 and 207, each of which is provided with a pair of diametrically disposed bosses 208 extending from one face of the plates in parallelism with the shaft 202. The opposite face of each end plate is recessed or cut out to receive therein a gear wheel 209 which is secured to the shaft 202 and a pair of pinions 15 210 that mesh at diametrically opposite points with the gear 209. Each pinion 210 is mounted on one end of a shaft 211 that extends centrally through one of the bosses 208 and carries a sprocket wheel 212 at its other end. It will be seen that sprockets 212 will be continuously rotated through the driving elements just described.

Two pairs of radially projecting arms 213 are carried by the end plates and extend lengthwise therefrom in opposite directions, each of the arms 25 being mounted at its inner end on one of the bosses 208. A coiled torsional spring 214 is mounted on each boss intermediate the end plate and the arm, and has its ends fixed to the plate and the arm respectively. The springs normally 30 yieldably maintain the pairs of arms in parallelism and in a common plane. One of the heretofore mentioned carrier conveyor chains 12 is carried by each of the arms 213, each chain extending around the sprocket 212 at the inner end of 35 the arm and around a sprocket wheel 215 mounted on the outer end of the arm. Thus, upon rotation of the carrier 10, the underside of the material is engaged by the chains of one pair of arms and lifted into contact with the conveyor 40 chains 11, the driven chains 11 and 12 delivering the material to the chains 11a and 13, as heretofore described.

Carrier driving mechanism

45 As shown in Fig. 16A, a ring gear 216 is suitably secured to the recessed face of the end plate 206 by bolts 217. A friction slip clutch 218, of any ordinary type, is mounted on the shaft 202 and frictionally drives a gear 219 which drives a gear 220 through intermediate driving gears 221 and 222. The gear 220 is mounted on a sleeve 223 which in turn drives a concentric shaft 224 through a jaw clutch 225, and the carrier 10 is rotated about the axis of the shaft 202 by a gear 50 226 keyed to the shaft 224 and meshing with the ring gear 216.

Starting and stopping of the carrier mechanism is controlled by the jaw clutch 225 whose jaws are brought into engagement with the cooperating 55 jaws on the sleeve 223 by the energization of a solenoid 228. The operating connections between the clutch 225 and the solenoid 228 are the same as the connections between the clutch 172 and the solenoid 175 of the heretofore described feeder carrier mechanism. In fact, it is pointed out that the driving mechanism for the catcher rotary carrier 10 is substantially the same as the driving mechanism for the feeder rotary carrier 18, the elements 223, 224, 225, 226 and 228 of the carrier 10 corresponding to the elements 169, 171, 172, 173 and 175 of the feeder carrier 18. Thus, when the flag 8 operates, it actuates a switch 230 through links 231 and 232 to energize the solenoid 228, whereupon driving engagement between the 70 clutch members 223 and 225 is effected to cause

rotation of the carrier 10 a half revolution. A cam 233, which corresponds to the cam 109 of the feeder, operates through bell crank lever 234 and link 235 to actuate switch 236 and cause de-energization of the solenoid 228. The carrier 10 is brought to rest at the end of its 180° movement by operation of the mechanism in the same manner as the carrier 18 is brought to rest.

Conveying mechanism

10 A bevel gear 238 keyed on the shaft 202 within the casing 201 meshes with a bevel pinion 239 which is mounted on a shaft that carries bevel gear 240 in mesh with bevel gear 241 which is mounted on an upright shaft 242. The shaft 242 drives a shaft 243 through bevel gears 244, and a sprocket wheel 245 on shaft 243 drives a sprocket wheel 246 through chain 247. Sprocket 246 is mounted on a shaft 248 and drives a parallel shaft 249 through gears 250, the shafts 248 and 249 being journalled in suitable bracket bearings secured to the forward upright supports 251. The shafts 248 and 249, respectively, carry pairs of sprockets around which the cooperating conveyor chains 11a and 13, respectively, are trained and extend forwardly over the rolls 2-3 and are trained around sprockets carried by parallel shafts 252 and 253 that are journalled in the forwardly extending ends of the uprights 251. The lower runs of the chains 13 also extend around idle sprockets 254 and thence downwardly around sprockets carried by a shaft 255 which is journalled in bearing brackets 256 secured to the uprights 251.

15 One end of a bracket arm 257 is supported on the shaft 248 and at its rear end carries a pair of sprockets around which the pair of conveyor chains 11 are trained. The chains 11 extend around sprockets mounted on the shaft 248 and are driven thereby. The bracket arm 257 is yieldably supported by a rod 258 and opposed springs 259 and 260 carried thereby at opposite sides of a plate 261 which is secured to rearwardly extending frame bars 262. It will be apparent that when the material is raised by the carrier 10 into engagement with the underside of the chains 11, the spring 260 will be compressed somewhat by upward rocking movement of the arm 257 and that the pair of arms 213 of the carrier 10 will be rocked downwardly slightly on their bosses 208 and tension the torsion springs 214, whereby the respective conveyor chains 11 and 12 are brought into parallelism with the material therebetween and positively advance the material forwardly to the conveyor chains 11a and 13. Further, the resistance of the springs 214 and 260 gradually overcomes the frictional driving force of the friction clutch 218 and the carrier is brought to rest with a minimum of shock at its intermediate material discharging position. Completion of the rotary movement of the carrier is effected when the trailing edge of the material passes beyond the forward end of the chains 12.

20 A sprocket chain 263 is driven from the lower end of the vertical shaft 242 and drives a shaft 264 journalled in the brackets 256 in parallelism with the shaft 255, it being recalled that the shaft 255 is driven by the chains 13. The shafts 255 and 264 are provided with sprocket wheels around which the cooperating upper and lower conveyor chains 9 are trained and extend forwardly and around sprockets provided on parallel shafts 265 journalled in extensions of the brackets 256. Thus, the material is received by the conveyor chains 9 and delivered to the skid bars 9a.

25 30 35 40 45 50 55 60 65 70 75

The skid bars are supported on the upper ends of push rods 266 that are suitably supported by brackets 267 and 268 and are adapted to be raised and lowered by bell crank rocker arms 269 that are pivotally mounted on the brackets 267. The rocker arms 269 are pivotally connected to an operating bar 270 that at its rear end is connected to a bell crank lever 271 that is secured to a rock shaft 272. A solenoid 273 has its armature connected by a link 274 to the bell crank 271. When the solenoid 273 is energized, the bell crank 271 and the shaft 272 is rocked and causes the bar 270 to move to the left as viewed in Fig. 16, such movement of the bar 270 actuating the rocker arms 269 to permit the rods 266 and the skid bars 9a to gravitate downwardly, for a purpose to be hereinafter described. A hand lever 275 is also secured to the rock shaft 272, so that the skid bars may be manually lowered in the manner described, at any desired time.

A lever arm 276 is secured to the rock shaft 272 and is connected by a vertically extending rod 277 to a lever arm 278 secured to a rock shaft 279 that is journalled on a cross beam 280 supported by uprights 281 at the rear end of the catcher platform. Counterweights 282 are suspended from the end of the lever arm 278 and serve to maintain the skid bars in their normal elevated position. An arm 283 is keyed to the shaft 279 and is pivotally connected to one end of a forwardly extending bar 284 whose other end is pivotally connected to one arm of a crank lever 285 pivotally mounted on a pin 286 supported on the frame bars 262. The other arm of the crank lever 285 is pivotally connected to one end of a depending supporting rod 287 having pivotal connection at its lower end with a centrally disposed bracket arm 288. At its rear end, the arm 288 is pivotally supported on a cross shaft 289 journalled in bearing brackets 290 of the cross beam 280.

The shaft 289 carries sprocket wheels 291 around which conveyor chains 292 are trained and extend forwardly and around sprocket wheels 293 journalled on the forward end of the arm 288. A cross shaft 294 is journalled in the brackets 290 in parallelism beneath the shaft 289 and carries sprocket wheels 295 around which conveyor chains 296 are trained and extend forwardly and downwardly and are trained around sprocket wheels 297 suitably journalled in brackets mounted on the base of the catcher.

As heretofore mentioned, the skid bars are normally maintained in their elevated position by the counterweights 282, in which position they are above the upper runs of the conveyor chains 296, so that material deposited on the skid bars will not be moved rearwardly through engagement with the chains 296. Also, the counterweights through the heretofore described connections, serve to maintain the upper discharge conveyor 292 in a raised position, so that raising of the material from the skid bars by the carrier 10 for delivery thereof by the conveyors 11 and 12 back to the feeder will not be obstructed by the discharge conveyor 292. However, when the solenoid 273 is energized or the handle 275 operated to rock the shaft 272, the skid bars 9a are lowered to deposit the material thereon onto the conveyor 296 while the shaft 279 is rocked to cause the arm 288 to swing downwardly and bring the conveyor chains 292 into engagement with the top of the material. The conveyor chains 292 and 296 cooperate to effect discharge of the material from the catcher.

The discharge conveyor chains 292 and 296 are constantly driven from the vertical shaft 242, which shaft has driving engagement with a rearwardly extending shaft 298 through bevel gears 299. The shaft 298 has driving engagement with the shaft 289 through bevel gears 300. A gear wheel 301 keyed to the shaft 289 meshes with a gear wheel 302 keyed to the parallel shaft 294.

Instead of employing a catcher having the structural characteristics herein set forth, the catcher disclosed and described in my prior Patent No. 1,487,819 may be used, if desired.

Operation

According to my method, the sheets, packs, bars, or other units of material are handled in pairs substantially throughout the rolling operation. The units of material are first properly spaced from each other and then successively fed through the rolls, one unit being returned from the back to the front of the roll stand while the other unit is being fed through the rolls. I prefer that the units be fed through the rolls in a substantially horizontal plane, lifted to the top of the roll stand, returned horizontally to the front of the roll stand and then lowered to a position opposite the bite of the rolls. I prefer to control the movement of the units of material with respect to each other so that there is no possibility of interference between the units, and, generally speaking, the operation of the machine may be controlled by the passage of the sheets.

Also according to my method I momentarily stop the movement of the units of material before they are fed to the rolls in order to align and center the units before feeding them to the rolls, and I may match pairs of units by stopping one unit in its cycle of movement, and holding it stationary until it is overtaken by a succeeding unit. I prefer to carry out this operation in an elevated position in front of the roll stand, and thereafter accurately align and center the pack so formed in a position directly in front of the bite of the rolls.

As an example of the operation of the machine, assuming the rolls to be rotating in the direction shown by the arrow in Fig. 2, the driving motors of the feeder and catcher are started, which results in the main conveyor chains 7 and the dog chain 13 of the feeder being driven while the rotary carrier mechanism remains idle. At the same time, the various chains of the catcher and the carrier 10 are being driven, the chains being in the position illustrated in Fig. 2 of the drawings.

To start the operation of the machine, the hooks 115 and 116 are depressed by operation of the pedals 130 or 132, depending upon whether the machine is controlled from the pulpit P or from the rear end of the feeder, and a sheet bar is fed to the machine by any suitable means and deposited on the main conveyor chains 7. When the sheet bar has passed the rear hooks 115, the latch 124 is released by means of one of the pedals 131 or 133, thus causing the hooks 115 and 116 to be raised. The first sheet bar then travels along until it engages the hooks 116 where further movement is prevented, the main conveyor chains 7 merely sliding along underneath the bar, while the dog chain urges the bar against the hooks, the chain being stopped due to the slippage of the clutch 45.

In the meantime, the operator feeds another sheet bar to the machine, which bar is stopped by the rear hooks 115. By this means, the bars

may be spaced so that they will be passed through the rolls to the catcher and back to the feeder in spaced relationship.

Thereafter, the pedal 130 or 132, as the case 5 may be, is depressed to withdraw the hooks from the path of the sheet bars allowing them to be fed forwardly towards the rolls by the conveyor chain. Movement of the pedal also results in the engagement of the one revolution clutch 61 which 10 causes the pushers 50 and 51 to be actuated to urge the bar into the bite of the rolls. The action of the pushers is ordinarily necessary only in the case of short material such as sheet bars. After the material has been elongated by the rolling 15 operations, the pushers are not necessary to properly feed the material into the rolls.

The first sheet bar is passed through the rolls and moved by the chains 9 onto the skid bars 9a, the bar depressing the flag 8 which when released 20 by passage of the bar actuates switch 230 which energizes the solenoid 228 to cause the clutch 225 to engage, thereby causing the carriage to swing in a clockwise direction, as illustrated in Figs. 2 and 16 of the drawings, bringing the bar up 25 beneath the upper chain 11, the carriage 10 stopping at this intermediate discharge point through slippage of the friction clutch 218, as heretofore described. Thereafter, by the co-action of the chains 11 and 12 and the chains 11a and 13, the 30 bar is delivered onto the arms 14 of the rotary carrier mechanism of the feeder, the carrier completing its 180° movement when the bar moves from between the chains 11 and 12. In being so delivered, the bar raises and lowers the flag 35 switch 15 which energizes the solenoid 175 to cause the clutch 172 to engage, thus resulting in a clockwise rotational movement of the carrier 18 of 180°. The flag switch 15 also controls the action of the retarding hooks 17 so that the sheet 40 bar is retained adjacent the outer ends of the arms 14.

In the meantime, the second sheet bar, being released from the rear hooks 115, has traveled forwardly to be fed to the rolls in proper timed relationship with the feeding of the first sheet bar, that is, at about the time, the first sheet bar is being delivered by the catcher back over the rolls. When necessary, the pushers can be actuated by the manual control mechanism to assist 50 in feeding the bar into the bite of the rolls.

After the two sheet bars have been started into the machine, its operation is completely automatic so far as the feeding, catching, and returning of the material is concerned. It is only necessary for the operator properly to adjust the rolls of the mill and to operate the controls to match the bars and remove them from the machine when sufficient elongation has been obtained. This automatic operation is obtained substantially as follows:

When the first sheet bar has been deposited on the arms 14, thus initiating the rotational movement of the rotary carrier 18, the cam 62 in response to movement of the carrier, and acting 65 through the follower 128 and the associated linkage functions almost immediately to release the latch 124, thus allowing the hooks 116 to be raised into the path of the material on the conveyor chains. The rotation at the carrier 18 results 70 in the material being deposited on the chains, the hydraulic check mechanism 140 being operative to slow down the carrier as the material is brought into contact with the chains.

Shortly after the material has been deposited 75 on the conveyor chains by the arms 14, and as a

result of the further rotation of the carrier, the cam 109 through the follower 110 and associated linkage actuates the clutch 108 which causes rotation of the pulley 104 and results in the side matching plates 97 being brought smartly towards each other and into engagement with the edges of the bar, thus centering the bar with respect to the mill rolls. Thereafter, the cam 62 through the cam follower 63 and its associated linkage functions to pull hooks 116 down out of the path of material and also to actuate the driving mechanism for the pushers 50, resulting in the bar being fed again to the rolls. This same cycle of operations is repeated successively with the second bar which is deposited on the arms 14 and the cycle may be carried out automatically until the desired elongation has been obtained.

If it is desired to match the two bars, the automatic control for the solenoid 175 is manually cut out by switches, not shown, disposed either at the front of the machine or in the pulpit. The solenoid is prevented from functioning while the first bar is deposited on the arms 14 so that the arms remain in position ready to receive the second bar which is deposited on top of the first. Before the second bar is delivered to the arms, the manual cut out for the solenoid is released so that the flag switch 15 automatically controls the operation of the machine to cause the rotation of the carrier mechanism and to deposit the pack on the conveyor chain 1. There the two bars are accurately aligned by means of the side matching plates and by means of the dogs 79 which engage the rear edges of the bars while they are being held against motion by the hooks 116.

At this stage, it may be desirable either to feed a similar pack consisting of two sheet bars to the machine and roll the two packs together in the machine, or to allow the machine to feed the first pack to the catcher and then by energizing the solenoid 273 by means of a manually actuated switch, not shown, cause the discharging conveyors 292 and 296 of the catcher to deliver the matched sheets to the platform at the rear thereof, from which point they may be sent to the furnace for reheating, while another cycle of operations is started with another pair of sheet bars.

Operation of the machine is substantially the same whether bars, sheets or packs are being handled, the only difference being that with longer material the pushers, and in some instances, the dogs on the dog chain, will not come into play. Also, the material may slide all the way onto the arms 14 and partially rest on the supporting bars 138. However, generally speaking, the machine is capable of automatic operation, under the control of the operator as described, and the operation is substantially the same regardless of the material being handled.

After the material has been sufficiently reduced in gauge and when the packs have been elongated to a predetermined extent that the flag switch F is operated thereby, the material is automatically discharged from the catcher and delivered to the opening platform. The automatic flag switch F (Fig. 16) energizes the solenoid 273, whereby the skid bars 9a are lowered to deposit the material onto the conveyor 296, and the upper conveyor 292 is forced downwardly into engagement with the top of the material and cooperating with the conveyor 296 discharges the material from the catcher.

In connection with the operation of the machine, it is important to note that substantially all of the various functions can be controlled manually as well as automatically. For example, 5 the side matching plates can be actuated whenever necessary, as can the pushers.

The retarding hooks can be raised and lowered at will and the motion of the rotary carrier can be stopped. Furthermore, it is to be noted that 10 by reason of the various slip clutches and automatic protective devices no damage can be done to the machine even though material be caught therein so that a blockade occurs.

From the foregoing description of a preferred 15 form of my invention, it will be seen that I have provided a method of rolling metal and of feeding metal to the rolls of a rolling mill whereby the rolling operation can be carried out with great speed, accuracy and efficiency. By my method, 20 the cost of the rolling operations will be greatly reduced as compared to present practices. By reason of the fact that I am able to handle relatively large quantities of metal simultaneously, the tonnage life of the rolls of the mill is greatly 25 increased. Furthermore, because of the rapidity of my method, the heating cost is substantially decreased as well as the cost of power and lubricants. Because I am able to roll packs containing 30 a greater number of plies than has heretofore been possible, the accuracy of the finished product is greatly increased. This feature also results in a saving in wear and tear on the surfaces of the rolls.

By my method, I am able to utilize the rolls 35 a large percentage of the time, for the material being rolled is handled in pairs substantially throughout the rolling operation, one pack of material being passed through the rolls while another pack is being returned from the back to 40 the front of the rolls for another pass so that the packs follow each other through the rolls in rapid succession. By reason of this feature and by reason of the speed of operation of my method, the idle time of the rolls is greatly reduced.

45 It will also be seen that I have provided a machine adapted efficiently to carry out my method of rolling sheets and to obtain the advantageous results outlined above. Furthermore, my machine is of sturdy and fool-proof construction and is provided with sufficient safeguards and automatic protective devices so that it can be operated without danger of damage to the machine or the material which is being rolled.

Various changes and modifications in my method and apparatus all within the scope of my invention will be apparent to those skilled in the art. It is accordingly to be understood that my patent is not limited to the specific embodiment given herein by way of example, or in any manner other than by the appended claims when given the range of equivalents to which my patent may be entitled.

I claim as my invention:

1. In a feeder for a sheet mill to which freshly 50 rolled sheets are delivered from the rearward side of the roll stand, the combination of a rotatable element having a plurality of tangentially extending arms fixedly mounted thereon for receiving said sheets, and means for rotating 55 said element to move the sheets to a position from which they may be fed to the rolls and to advance other arms to a position for receiving other sheets.

2. In a sheet rolling mill having a catcher 70 positioned behind the rolls for catching sheets

and delivering them from the back to the front side of the roll stand, a feeder having a rotatable element with a plurality of tangentially extending arms fixedly mounted thereon adapted to receive sheets delivered by the catcher and means controlled by movement of the sheets for rotating said element when sheets are delivered thereto.

3. In a machine for feeding material to the rolls of a roll stand, the combination of conveying means adapted to deliver material into the rolls, a rotatable element movable in one direction, through a completely annular path and adapted to receive material passed from the back to the front of the rolls and to deposit such material on the conveyor, and means for retarding the movement of the rotatable element as the material is being deposited on the conveyor.

4. In a feeder for a sheet mill, the combination of means adapted to receive material delivered from the back to the front of the mill, and movable abutments controlled by movement of the sheet, for stopping the material so delivered with the rearward end of the material closely adjacent the mill.

5. In combination with the rolls of a roll stand, a catcher adapted to receive material from the rolls and to pass the material back over the rolls, a feeder adapted to receive material from the catcher and feed material between the rolls, and movable abutments controlled by movement of the sheet, for stopping the material in its delivery by the catcher to the feeder with the rearward end of the material closely adjacent the roll stand.

6. In a sheet feeding mechanism, means for retarding the movement of material therein comprising a series of levers pivoted adjacent their upper ends and adapted to hang down into the path of the material, means for locking said levers against swinging movement in one direction, and means controlled by the movement of material for controlling said locking means.

7. In a machine for feeding material to the rolls of a roll stand, the combination of a conveyor adapted to deliver material to the rolls, means movable down from a plane above the conveyor, for depositing material on the conveyor, means for longitudinally aligning the material on the conveyor, and means actuated by the said depositing means for laterally aligning and centering the material on the conveyor.

8. In a feeder for a rolling mill, the combination of conveying means for moving material toward the bite of the rolls, a carrier for depositing material on said conveyor, and means controlled by movement of said carrier for holding material against movement on said conveyor.

9. In a feeder for a rolling mill, the combination of a conveyor for moving material toward the bite of the rolls, a carrier for depositing material on said conveyor and means actuated by movement of the carrier for aligning and squaring said material prior to its entering the bite of the rolls.

10. In a feeder for a rolling mill, means for advancing material into the bite of the rolls, means for delivering material to the feeder from the back of the rolls, a carrier for moving material from said last-named means to said first-named means, means for restraining movement of material from the back to the front of the rolls releasable by said carrier, and means for initiating movement of said carrier dependent upon movement of the material thereupon.

11. Rolling mill apparatus comprising a pair of rolls, a feeder at the front side of the rolls for advancing material into the bite of the rolls, a catcher at the rear side of the rolls for returning the rolled material to the front side of the rolls, means for depositing a unit of returned material upon the said feeder while the catcher is being operated to return another rolled unit of material, a stop device for preventing the first-named unit of material from being again advanced into the bite of the rolls until the second-named unit of material has been deposited on the first-named unit by the said depositing means, and means for thereupon releasing said stop device to permit the two units to be advanced into the bite of the rolls.

12. Rolling mill apparatus comprising a pair of rolls, a feeder at the front side of the rolls for advancing material into the bite of the rolls, a catcher at the rear side of the rolls for returning the rolled material to the front side of the rolls, means for depositing a unit of returned material upon the said feeder while the catcher is being operated to return another rolled unit of material, a stop device for preventing the first-named unit of material from being again advanced into the bite of the rolls until the second-named unit of material has been deposited on the first-named unit by the said depositing means, means for matching and aligning the said two units of material, and means for thereupon releasing said stop device to permit the two units to be advanced into the bite of the rolls.

13. Rolling mill apparatus comprising a pair of rolls, means for depositing and feeding one unit of material to the bite of the rolls, means for simultaneously returning a previously-rolled unit of material from the rear side of the rolls to the front side thereof, selectively operable means for retaining one unit of material at the front side of the rolls until the other unit of material has been deposited thereon, and means for releasing the retaining means and rendering the feeding means operative to advance the two units of material into the bite of the rolls.

14. The method of rolling sheet metal which includes the step of passing one unit of material through the rolls while returning a similar unit from the back to the front of the roll stand, and moving the material in its front and back movements in substantially straight horizontal lines, restraining the movement of the material in its movement away from the rolls in either direction to substantially its own length, and in matching similar units of material by holding one of the units in horizontal position at about the end of its movement away from the rolls until the other sheet overtakes it.

15. The method according to claim 14 which includes the additional steps of moving the matched units of material in a direction normal to the plane thereof to a position in line with and in front of the bite of the rolls, aligning the sheets by forces acting on the front and side edges of the sheets, and thereafter passing the matched and aligned sheets through the rolls.

16. The method of rolling sheet metal (whether bars, sheets or packs) which includes working the material in pairs of units by repeatedly and alternately passing one unit through the rolls while simultaneously forcing the other unit in a movement from the back to the front of the roll stand, and in restraining the movement of the returning unit until the first unit has been initially moved toward the bite of the rolls.

17. The method of rolling sheet metal which consists in working the material in pairs of units by passing one unit toward, through, and away from the rolls in substantially a horizontal plane while returning the other unit from the back to the front of the rolls in substantially a horizontal plane spaced from the first plane, the unit at the rear side of the rolls being raised for return movement while the unit on the other side of the rolls is being lowered, and matching said units by restraining one in its path of movement until overtaken by the other.

18. The method of rolling sheet metal which consists in working units thereof in pairs by passing one unit through the rolls while returning the other unit from the back to the front of the rolls, and holding one unit at rest behind the rolls until the whole of the other unit is moved away from the rearward vertical zone of the rearward face of the rolls.

19. The method of rolling sheet metal which consists in working the material in pairs of units by passing one unit toward, through, and away from the rolls in substantially a horizontal plane, while returning the other unit from the back to the front of the rolls in substantially a horizontal plane spaced from the first plane, the unit at the rear side of the rolls being raised for return movement while the unit on the other side of the rolls is being lowered, and matching said units by restraining one in its path of movement until overtaken by the other, without modifying movement of the latter unit.

20. The method of rolling sheet metal which consists in working the material in pairs of units by repeatedly and alternately passing one unit through the rolls from front to rear, while returning the other unit from the rear to the front of the rolls, matching said units by restraining one in its path of movement until overtaken by the other without interrupting the movement of the latter and continuing the movement of the matched pair directly in the order of movements of the latter unit as if the first unit had not been matched to and moved with the second unit.

21. The method of rolling sheet metal which consists in working the material in pairs of units by repeatedly and alternately passing one unit through the rolls from front to rear, while returning the other unit from the rear to the front of the rolls, matching said units by restraining one in its path of movement until overtaken by the other and feeding the matched units, all without interrupting the normal movement of the said other unit.

22. Apparatus for rolling metal, which includes means for feeding one unit of material through the rolls, means for simultaneously returning another unit from the back to the front of the roll stand, means for moving the material downwardly to the feeding means adjacent to a vertical face of the rolls, and means controlled by movement of the returned units for positively stopping at least the shorter units of material in their movement across the plane of the face of the rolls at a point where substantially no more than the full length of the material lies beyond the plane of the vertical face of the rolls.

23. In a rolling mill the combination of a pair of rolls, a feeder on the front side of the rolls, having a conveying device for advancing material into the bite of the rolls and a catcher on the back side of the rolls for receiving material and transmitting it over the rolls to said feeder, said feeder having a periodically rotatable ma-

- 5 terial-carrying element that is disposed mainly above the conveying device and moves in a plane perpendicular thereto, said carrying element intersecting the plane of the said conveying device during its rotative movement to discharge material to the conveyor, and means responsive to the passage of material from the catcher onto said carrying element for the feeder for initiating rotative movement of said carrying element.
- 10 24. In a rolling mill the combination of a pair of rolls, a feeder on the front side of the rolls, having a conveying device for advancing material into the bite of the rolls and a catcher on the back side of the rolls for receiving material 15 and transmitting it over the rolls to said feeder, said feeder having a periodically rotatable material-carrying element that is disposed mainly above the conveying device and moves in a plane perpendicular thereto, said carrying element intersecting the plane of the said conveying device during its rotative movement to discharge
- 20

material to the conveyor, and means for preventing delivery of material from the catcher to the feeder releasable only by movement of the carrying element for the feeder to a predetermined position.

25. In a rolling mill, the combination with a pair of rolls, of a conveyor for advancing material into the bite of the rolls, a catcher for receiving the rolled material and transmitting it back over the rolls, a carrier normally positioned to receive the material from the catcher and movable in one direction in an annular path to deposit the material on the conveyor, means for initiating movement of the carrier, dependent upon reception of material thereby, and a stop device movable into position to prevent delivery of material from the catcher to the said carrier when the carrier is moved out of its normal position.

5

LAWRENCE C. STEELE. 20
